UNITED STATES PATENT OFFICE

HARRY B. WHITE, OF CANTON, OHIO, ASSIGNOR TO THE HOOVER COMPANY, OF NORTH CANTON, OHIO, A CORPORATION OF OHIO

SUCTION CLEANER

Application filed March 17, 1930. Serial No. 436,365.

The present invention relates to suction cleaners in general and more particularly to height-adjusting means for the nozzle of a suction cleaner. Specifically the invention 5 comprises the provision of means for adjusting the position of the front supporting wheels of the suction cleaner relative to the cleaner itself thereby serving to vary the position of the nozzle lips relative to the 10 surface covering.

The object of the present invention is to provide new and novel means for adjusting the nozzle height of a suction cleaner. A second object is to provide a simplified construction by which the front supporting wheels of the suction cleaner may be adjusted relative to the cleaner itself. A still further object of the present invention is the provision of a manually adjustable nozzle height determining 15 construction for a suction cleaner which is of simple construction and easily manufactured. Other and more specific objects will appear upon reading the following specification and taking into consideration the 20 drawings annexed thereto.

Referring now to the drawings:—

In Figure 1 is disclosed a side view of a suction cleaner embodying the present invention, with certain parts broken away.

Figure 2 discloses a bottom view upon the line 2—2 of Figure 1.

Figure 3 is a section upon the line 3—3 of Figure 2.

Figures 4 and 5 are views in perspective 35 of the supporting brackets.

Referring now to Figure 1 in particular, a suction cleaner is disclosed which comprises the usual parts including a motor casing 1, a fan casing 2, a nozzle casing 3 which is 40 made integrally with fan casing 2, a dust bag 4 which is attached to the exhaust outlet of fan chamber 2 which is not shown, the handle member 5 which is pivotally attached to the motor casing 1 in order that the cleaner may be moved about upon the surface covering, a rear supporting wheel 6 which is rotatably but non-adjustably secured to the motor casing 1, and front supporting 45 wheels 7, 7 which are adjustable relative to the

cleaner in a manner which comprises the present invention.

Pivottally mounted, as is clearly shown in Figure 2, to the side walls 8, 8 of the casting comprising the nozzle and fan casing 2 and 3 are the arms or brackets 9 and 10 which are secured in place by means of hollow rivets 11, 11. The supporting arm 9 comprises a body portion 12 which is formed from a suitable stamping and which is provided 55 with off-set and spaced curved arms 13, 13 which form a cylindrical seat adapted to non-rotatably support one end of the wheel-carrying axle 14 which extends transversely of the cleaner and immediately behind the suction nozzle and also immediately below the side walls 8, 8, aforescribed. At the pivoted end of body portion 12 of bracket 9 a straight arm portion 15 extends at right angles. The rear face of arm 15 is parallel to the transversely extending portion of the wall 8 upon that side of the cleaner and is adapted to be contacted by the screw-threaded adjusting member 16 which is seated within an internally threaded enlarged portion 17 of the 60 wall 8.

The bracket or arm 10, see Figure 5, which is pivoted to the remaining wall 8 comprises merely a straight body portion which is provided with off-set curved arms 18, 18 which 65 form a cylindrical seat for the end of the axle 14 opposite to that enclosed by the arms 13, 13 of bracket 9. In both brackets 9 and 10, the arms which form the seat for the axle 14 are stamped from the body portion of the 70 bracket and are of sufficient length and rigidity to prevent any looseness or play of the axle 14 therein. The supporting wheels 7, 7 are mounted upon the opposite ends of the axle 14 immediately outside the side walls 8, 80 and are secured relative to the axle by means of securing screws 19, 19 as shown in Figure 2.

Substantially midway between the walls 8, 8 is a spring member 20 which is secured by 85 means of a screw 21 to the wall of the fan casing 2. The extended arms of the spring 20 contact the underside of the axle 14 and serve at all times to exert an upward force 90 on that member which tends to pivot the 100

brackets 9 and 10 about their supporting pivots until such pivotal movement is limited by contact of the arm 15 with the adjusting member 16.

In order that the adjustment of the nozzle of the cleaner relative to the surface covering may be readily observed by the operator, a plate or pointer 22 is provided which is mounted upon the axle 14 and rigidly secured to the underside of bracket 9 by means such as a rivet 23. At the upper end of arm or plate 22, which extends closely adjacent the exterior of wall 8, is provided a protruding finger 24 which is adapted to indicate to the observer, through pointing to one of several markers made upon the walls 8 as shown in Figure 1, the exact adjustment of the suction cleaner nozzle relative to the surface covering. The plate and finger being fixedly carried by the shaft 14 and bracket 9 is moved as they are pivoted and so indicates the changes in nozzle position.

To adjust the nozzle height of a suction cleaner embodying the present invention, it is only necessary for the operator to manually rotate the member 16. If it is desired to raise the nozzle the member 16 will be advanced through the wall 8 causing the bracket 9 to be pivoted about its pivot point 11 through the force exerted upon the contacting arm 15. Because of the substantially rigid relation of the brackets 9 and 10 and the axle 14, the bracket 10 is also pivoted about its pivot point and the supporting wheels 7, 7 are uniformly lowered relative to the cleaner proper thereby raising the suction nozzle from the surface covering. If on the other hand it is desired to lower the suction cleaner nozzle relative to the surface covering the adjusting member 16 is retracted through the wall 8 permitting the coil spring 20 to exert a rotating force directly upon the shaft 14, and so brackets 9 and 10, which is limited only by the contact of the arm 15 with member 16. The degree of adjustment is apparent at all times to the operator by means of the pointer or finger which indicates, by its position relative to the marks upon the nozzle casing, the relation of the suction cleaner nozzle to the covering.

I claim:

1. In a suction cleaner height adjusting construction, spaced supporting wheels, a common shaft extended between said wheels, 55 pivoted brackets connecting said shaft to a cleaner casing at spaced points, said brackets being each provided with a seat for said shaft extended in the direction of the shaft's length to prevent looseness, resilient means 60 contacting said shaft and urging said wheels in one direction, and manually adjustable means comprising a threaded member in contact with one of said brackets and adapted to move said wheels against the force exerted 65 by said spring.

2. In a suction cleaner height adjusting construction, spaced supporting wheels, a common shaft rotatably supporting said wheels, spaced brackets extended perpendicularly to said shaft and pivoted to a casing, each bracket being provided with a seat formed of spaced-folded-deformed sections extending parallel to and closely enclosing said shaft, and means to pivot one of said brackets to effect the adjustment of said wheels, said brackets being unconnected except by said shaft.

Signed at North Canton, in the county of Stark, and State of Ohio, this 11th day of March, A. D., 1930.

HARRY B. WHITE.
